UNITED STATES PATENT OFFICE.

JULIA BETTNER BERRY, OF NEW YORK, N. Y.

MANUFACTURE OF FABRIC FOR HATS, &c.

SPECIFICATION forming part of Letters Patent No. 339,521, dated April 6, 1886.

Application filed March 12, 1886. Serial No. 194,930. (Model.)

To all whom it may concern:

Be it known that I, JULIA BETTNER BERRY, a citizen of the United States, residing in the city of New York, in the State of New York, 5 have invented a new Fabric, and as a new Article of Manufacture a Lady's Hat made therefrom, of which the following description is sufficient in law.

In the accompanying drawings, Figure 1 represents a lady's hat; Fig. 2, a sheet of tissue-paper divided off into squares; Fig. 3, a square of tissue-paper; Fig. 4, a tube and rod for making tissue-paper forms, and Fig. 5 a tissue-paper form for making fabric.

15 My invention consists of a fabric the base or under side of which is cloth, lace, or gauze, covered with a coating of glue-paste, upon which is set close together forms of tissue-paper that afterward are evenly trimmed to give 20 the fabric a uniform appearance.

My invention also consists in a new article of manufacture, or a lady's hat made from tissue-paper fabric.

To make the tissue-paper forms, the paper 25 is first cut into little squares about one inch in size. These squares are then laid over a tube about two inches long, and pressed through the tube by a rod, which neatly fits the tube. The paper comes out of the tube in the shape 30 of forms, or cups, or caps, which, by means of the rod, are pressed upon the paste-covered cloth with the cut edges upward. As soon as the cloth is covered the edges of the forms 35 are neatly trimmed with a pair of shears, so as to give the fabric a uniform appearance.

In making a hat the hat-body is first covered

with tissue-paper of the color selected for the hat. Then after the glue-paste has been applied the tissue forms are closely set together, to make the entire outer covering of the hat. 40 When the edges of the forms have been trimmed and the hat bound, it is ready for the milliner. Instead of tissue-paper, gold and silver paper or any suitable thin paper or crape may be used with equal utility and unique effect. 45

This new fabric may be made of any color or shade of paper. Different designs, as a star or crescent, or flowers of a harmonizing color may be incorporated into the fabric. Even a strip or band of another color, made of tissue 50 forms can be employed with beautiful effect.

This new fabric may be used for other purposes than for the manufacture of ladies' hats as costumes for fancy-dress balls, picture-frames, and decorations. 55

I claim—

1. A fabric made of cloth, lace, or gauze, coated with glue-paste, and then covered with tissue-paper forms, constructed in the manner described. 60

2. As an article of manufacture, a lady's hat made of a fabric of which the outer covering is tissue-paper forms, constructed as described.

In testimony whereof I hereunto set my hand and seal at the city of Washington, in presence of two attesting witnesses, on this the 11th day of March, A. D. 1886.

JULIA BETTNER BERRY. [L. S.]
